CLAIM

The ornamental design for a machine for earth-moving, material handling, lifting, and/or construction, as shown and described.

DESCRIPTION

FIG. 1 is a top, front, and right-side isometric view a machine for earth-moving, material handling, lifting, and/or construction showing the new design.

FIG. 2 is an enlarged top, back, and right-side isometric view of the part of the machine that bears the claimed design.

FIG. 3 is a top plan view of the part of the machine that machine seen in FIG. 2.

FIG. 4 is a right-side elevation view of the part seen in FIG. 2.

FIG. 5 is a back elevation view of the part seen in FIG. 2.

FIG. 6 is a left-side elevation view of the part seen in FIG.

2.

FIG. 7 is a front elevation view of the part seen in FIG. 2.

FIG. 8 is a bottom plan view of the part seen in FIG. 2.

FIG. 9 is a rear elevation view of the machine for earth-moving, material handling, lifting, and/or construction seen in FIG. 1, showing a second embodiment of the design, which a mirror image of the first embodiment that is borne on a different part of the same machine.

FIG. 10 is an enlarged top, back, and left-side isometric view of the part of the machine that bears the second embodiment of the design.

FIG. 11 is a top plan view of the part seen in FIG. 10.

FIG. 12 is a rear elevation view of the part seen in FIG. 10.

FIG. 13 is a left-side elevation view of the part seen in FIG.

10.

FIG. 14 is a front elevation view of the part seen in FIG. 10.

FIG. 15 is a right-side elevation view of the part seen in FIG.

10; and,

FIG. 16 is a bottom plan view of the part seen in FIG. 10.

The broken lines in FIGS. 1, 6, 9, and 15 depict portions of the machine for earth-moving, material handling, lifting, and/or construction that form no part of the claimed design.

1 Claim, 8 Drawing Sheets
